US00D521997S

(12) **United States Design Patent** (10) **Patent No.:** **US D521,997 S**
(45) **Date of Patent:** **** May 30, 2006**

(54) **LCD MONITOR**

(75) Inventors: **Sang-Il Park**, Seoul (KR); **Jin-Sun Kim**, Seoul (KR)

(73) Assignee: **Samsung Electronics Co., Ltd.**, Kyunggi-do (KR)

(**) Term: **14 Years**

(21) Appl. No.: **29/231,924**

(22) Filed: **Jun. 10, 2005**

(51) **LOC (8) Cl.** **14-02**

(52) **U.S. Cl.** **D14/375**

(58) **Field of Classification Search** D14/371-376,
D14/125-129; 345/104, 156, 168, 173, 87,
345/1.1, 901-905; 341/12; 348/180, 184,
348/325, 739; 349/1, 2, 11, 58; 248/917-924
